CLAIM

The ornamental design for a bath brush as shown and described.

DESCRIPTION

FIG. 1 is a front perspective view of a bath brush, showing my new design;

FIG. 2 is a front elevational view thereof, the rear elevational view being a mirror image;

FIG. 3 is a left side view thereof;

FIG. 4 is a right side view thereof;

FIG. 5 is a top plan view thereof;

FIG. 6 is a bottom plan view thereof;

FIG. 7 is a partially enlarged view of area "7" in FIG. 1;

FIG. 8 is a partially enlarged view of area "8" in FIG. 1; and, FIG. 9 is an exploded, front perspective view thereof.

In the drawings, the dash-dash lines depict portions of the bath brush and form no part of the claimed design. The dot-dash lines shown in FIGS. 1, 7, and 8 are for the purpose of depicting enlarged view indicators, and form no part of the claimed design.

1 Claim, 6 Drawing Sheets
